UNITED STATES PATENT OFFICE.

ALFRED FISHER, OF DALLAS, TEXAS.

MATTRESS-DISPLAY RACK.

1,114,455.

Specification of Letters Patent. Patented Oct. 20, 1914.

Application filed August 9, 1913. Serial No. 783,956.

To all whom it may concern:

Be it known that I, ALFRED FISHER, a citizen of the United States, and a resident of Dallas, in the county of Dallas and State of Texas, have invented a new and Improved Mattress-Display Rack, of which the following is a full, clear, and exact description.

My invention has reference to mattress racks in which slideable trays are adapted to be projected beyond the front of the rack and supported in a tilted position for the proper display of the mattress.

It is the design of my invention to improve in various particulars racks of the indicated character, to the end that convenience in operation may be promoted, as well as simplicity of construction and economy of manufacture.

The invention will be particularly explained in the specific description following.

Reference is to be had to the accompanying drawings forming a part of this specification, in which similar characters of reference indicate corresponding parts throughout the views, and in which—

Figure 1 is a perspective view of a mattress rack embodying my invention, the parts being broken away; Fig. 2 is a sectional plan view; Fig. 3 is a fragmentary detail in vertical section; Fig. 4 is a detail in section on the line 4—4 of Fig. 3; Fig. 5 is a sectional side view of the carriage and controlling means for a supporting chain for the mattress; and Fig. 6 is a sectional end view of the devices shown in Fig. 5.

In constructing a practical embodiment of my invention, the rack is formed with a framework comprising corner posts 10, side bars 11 and front bars 12. There may be also a longitudinal bottom bar 13 for strength. The several corner posts, side bars and front bars are formed of angle-iron, and the side bars receive sliding trays 14 which are provided on the sides thereof, near the rear end of each tray, with running rollers 15, there being friction rollers 16 on the side bars 11, near the front of the rack. The side bars 11 form tracks for the running rollers 15. The said tracks extend at the front beyond the friction rollers 16.

With the described construction any tray 14 may be run outward on the bars 11 until the running rollers 15 pass the friction rollers 16 and contact with the front bars 12,

the latter forming a stop. In the outer position of the tray it may be tilted downwardly, with the running rollers 15 as an axis, to the position indicated in dotted lines, Fig. 1.

In order to support the tray in the tilted outer position each tray is formed with a downwardly-disposed hook 17 on the front thereof, which is adapted to engage in the links of an endless sprocket chain 18. The chain 18 hangs freely from a sprocket wheel 19, the shaft 20 of which is journaled in a carriage 21, the running wheels 22 of which travel on an overhead track 23. The track 70 is supported in any suitable manner; in the instance shown one end 23^a is secured to the top of the rack while the forward end is supported by a hanger cord 23^b, or the like, which may be, in practice, attached to a 75 ceiling. The cord 23^b connects with a strap 23^c on the outer end of the bar 23, the strap forming a stop limiting the outward movement of the carriage 21. On the shaft or pin 20 of the sprocket wheel 19 is a ratchet 80 wheel 24, adapted to be engaged by a pawl 25 which is pivoted between its ends on the carriage, one arm of the pawl having connection with a pull rope 26, to release the pawl for raising and lowering the tray 85 through the medium of the chain 18. The pawl serves to hold the chain and tilted mattress tray in a given position.

By mounting the chain on a carriage adapted to run forward and back, the chain 90 may be brought to a proper position, according to whether an upper or a lower tray is to be supported by the chain, the upper trays requiring, for a proper display of the mattresses thereon, that the chain be 95 in a position nearer to the rack than when the lower trays are to be supported.

By the described construction the mattress may be quickly brought to a position to be advantageously displayed, and readily 100 returned to the rack with a minimum of effort on the part of the salesman.

Having thus described my invention, I claim as new and desire to secure by Letters Patent:

1. A display rack of the indicated character comprising a tray support, a tray slideable on the support to be projected to an outer position in front of the support and adapted to tilt downwardly when in the 110 outer position, in combination with a suspension chain depending in front of the

rack, the tray having means to engage said chain.

2. The combination with a display rack having sliding trays adapted to be moved outward to project beyond the rack, the trays being adapted to tilt, of a carriage, an overhead track on which the carriage may travel forward and backward, a depending suspension means on the carriage for sup-

porting a tray, and means on the respective 10 trays to engage said suspension means.

In testimony whereof I have signed my name to this specification in the presence of two subscribing witnesses.

ALFRED FISHER.
